DESK FOR RECORD AND FILE CARDS

Ralph F. McCann, North Hollywood, Calif.

Application October 4, 1954, Serial No. 32,527

Term of patent 3½ years

(Cl. D33—7)

Fig. 1.

Fig. 2.

Fig. 1 is a perspective view of a desk for record and file cards with the cover omitted for convenience of illustration.

Fig. 2 is a side elevational view thereof with the conventional removable cover for the circular center compartment illustrated in broken lines.

The dominant feature of the design resides in the part shown in full lines.

I claim:

The ornamental design for a desk for record and file cards, substantially as shown and described.
